US00D815752S

(12) **United States Design Patent** (10) Patent No.: **US D815,752 S**
(45) Date of Patent: ** Apr. 17, 2018

(54) **BIOCHIP WELL**

(71) Applicant: **Randox Laboratories Ltd.**, Northern Ireland (GB)

(72) Inventors: **Stuart Jackson**, Northern Ireland (GB); **Ivan McConnell**, Northern Ireland (GB); **John Lamont**, Northern Ireland (GB); **Peter Fitzgerald**, Northern Ireland (GB)

(73) Assignee: **Randox Laboratories Ltd.** (GB)

(**) Term: **14 Years**

(21) Appl. No.: **29/510,481**

(22) Filed: **Nov. 28, 2014**

(51) LOC (11) Cl. **24-02**

(52) U.S. Cl.

USPC **D24/224**

(58) **Field of Classification Search**

USPC D24/224-230, 216, 150, 197; D10/103; D9/439, 455, 415, 425; 422/400, 65, 422/68.1, 500, 502-503, 510, 536, 422/552-553, 563; 206/528, 438, 443, 206/363, 368; 220/507; 257/701; 436/165; 506/7, 9, 13, 39-40; 435/283.1, 287.1, 287.2, 304.1

CLAIM

The ornamental design for a biochip well, as shown and described.

DESCRIPTION

FIG. 1 is a top perspective view of a biochip well showing my new design;

FIG. 2 is a bottom perspective view thereof;

FIG. 3 is a rear view thereof;

FIG. 4 is a front view thereof;

FIG. 5 is a side view thereof;

FIG. 6 is a top view thereof; and,

FIG. 7 is a bottom view thereof.
